UNITED STATES PATENT OFFICE.

JOHN F. CARVER, OF ROSLINDALE, MASSACHUSETTS.

DISPLAY-CONTAINER.

1,142,020.

Specification of Letters Patent. Patented June 8, 1915.

Application filed June 30, 1914. Serial No. 348,143.

To all whom it may concern:

Be it known that I, JOHN F. CARVER, citizen of the United States, residing at Roslindale, county of Suffolk, State of Massachusetts, have invented a certain new and useful Improvement in Display-Containers, of which the following is a specification, reference being had therein to the accompanying drawings.

10 The invention relates to a new and useful improvement in display boxes or containers.

It is a common practice to pack a certain number of small boxes of merchandise in a larger box or container, the said container being used also as a display holder which may be used to display the smaller packages while held in the container. To make the most attractive display in such containers as ordinarily constructed, the container 20 should be kept full all the time, that is, if one of the boxes is removed, as by a sale to a customer, it should be replaced by another box so as to always maintain a symmetrical appearance of the container.

25 The object of the present invention is to produce a display container which shall have the appearance of a full box, even after a considerable number of the small boxes have been removed from the container 30 and no replacement has been made.

The invention will be understood from the following description taken in connection with the accompanying drawings, and the novel features thereof will be pointed out 35 and clearly defined in the claims at the close of the specification.

In the drawings,—Figure 1 is a perspective view of a display container embodying the invention entirely closed. Fig. 2 is a 40 perspective view of the container showing the flap cover open to display the contents and give access to the small boxes within the container. Fig. 3 is a plan view of a blank formed of an integral sheet of material 45 which may be folded to form the container. Fig. 4 is a view of one of the small boxes held by the container.

Referring now to the drawings,—A represents the container and B the small boxes 50 which are packed in the container. The body of the container is of rectangular form of such size that a number of boxes B may be packed in the container and just fill it. The box is preferably of a knock-down form 55 made of a single sheet of paper, as shown in Fig. 3, as will be hereinafter described,

but not necessarily of that particular form. The top of the box is formed with a flap cover portion 1 which is of a width equal to one of the inclosed boxes B and is hinged or otherwise flexibly connected with one edge of the body of the box so that it can be thrown back, as shown in Fig. 2 to display the contents of the container or it may be shut, as shown in Fig. 1, to close the container. In the form of container shown for illustration it is adapted to hold six small boxes in each layer, three rows of two boxes each running widthwise of the container and there may be several tiers or layers in depth. The flap cover 1 is of a width equal to one of said small boxes B and of a length equal to two of said boxes and is symmetrically arranged to cover the middle row of small boxes. On the opposite sides of the said flap cover there are the cover portions 2, 3 respectively which are intended to remain permanently closed after the container is set up, each one of said portions 2, 3 covering, from front to rear, one of the rows of small boxes B. The flap cover 1 and the said top portions 2, 3 are paneled off with panel portions 4, 5; 6, 7; 8, 9; corresponding in size with the top face of the small boxes B and are preferably printed in facsimile of the face portion of said boxes B so that when the flap cover is closed the entire top of the container will have the appearance of a group of six of the small boxes and when the flap cover is open exposing two of the small boxes B the two end cover portions 2, 3 together with the two exposed boxes B, B will still have the same appearance of a container full of small boxes.

95 Preferably, the flap cover 1 is adapted to fold crosswise of the middle thereof, as shown in Fig. 2, and is formed with a tongue 10 which, when the flap cover is brought back to a vertical position, as shown in Fig. 2, may be engaged in a slot 26 or between one of the boxes B and the back side of the container to hold the flap cover in upright position and display the contents of the container. By reason of the flap cover also being in this upright position and folded in the middle, there is a full panel both on the front and the back of the flap cover which conspicuously displays the advertising matter in the panel similar to that on the 105 boxes, as already described.

110 Preferably the panels 4, 5 which form the

hinge cover are printed in inverted arrangement relative to each other on the flat blank so that when the cover is turned up in easel form as shown in Fig. 2 the reading on both 5 panels will be from the top down. It is obvious that the printing being all on one face of the blank, all of the panels may be printed by one impression.

When the salesman removes one of the 10 boxes in the middle tier, he can slide one of the boxes from the two end tiers toward the center to take its place, thus keeping the middle tier always full, but the space from which it was taken beneath the closed top 15 portions 2, 3 will not be noticeable to the outside observer even though the two end tiers be entirely taken away, and in looking down upon the container it will still appear as though it were entirely full. As the flap 20 cover comprises only a portion of the top of the container, the larger part of the boxes in the container are covered over even when the flap cover is turned back, and thus they are protected from dust and also from exposure to light which fades the boxes and 25 renders them less attractive. Moreover, the side portions of the container are supported and strengthened by the portions of the top which remain permanently closed.

30 As already stated, the box is preferably made of a single sheet of material cut out and scored, as indicated in Fig. 3, which shows the blank laid out flat. Referring to said Fig. 3,—the portion of the blank which 35 includes the panels 6, 7; 4, 5; 8, 9; will together form the top and flap cover of the container; it has a panel portion 11 which when the box is set up forms the front side of the box, a flat portion 12 which will be 40 folded along the dotted line between 12 and 11 to form the bottom of the container, a rear flap portion 13 which will form the rear side of the container, and two end flap portions 14, 15 which will form respectively the 45 two end portions of the container. The rear side portion 13 is formed with a narrow flap or tuck portion 16 which when the box is set up will be tucked in under the adjacent edge of the bottom forming flap 12, and glued 50 thereto and the two end panels 14, 15 are formed respectively with the tuck flap portions 17, 18 which will be tucked in between the said end portions 14, 15 and the bottom portion 12. There are also provided the 55 four rectangular corner tuck flaps 19, 20; 21, 22; which are turned and tucked in between the end portions 14, 15 and rear and front side portions 11, 13 respectively. The cover flap is formed out of the integral sheet 60 by slitting along the side lines 23 and 24 and along the front 25 following around the outline of the tongue 10 so as to form the tongue piece, and this will leave a notch 27 in the upper edge of the front wall 11, which 65 makes it convenient to remove the top front

box with the thumb or finger which may easily take hold of the front edge of the box at the point exposed by the notch. The blank will be scored or creased along the bending lines between the severed portions. 70

It is obvious that the form of the blank out of which the container is made may be varied, as there are many ways of forming knock-down boxes out of a single sheet and it is also obvious that the number of panels 75 may be varied for the permanent closed portion of the top of the box as well as for the cover and if desired the flap cover may be wide enough to cover two or more rows of small boxes from front to rear instead of 80 one row as shown.

The term hinged cover or hinged flap cover is intended to apply whether the cover is a separate portion hinged to the wall of the container, or whether it is integral with 85 the wall and creased or bent so that it will fold on the edge as shown in the drawings.

What I claim is:

1. A display container for boxes of merchandise, said container having a top cover, 90 a portion of said top cover comprising a portion movable with relation to the remaining top portion, said top portions being marked to represent a plurality of panels each of which is of a size and shape like the 95 top face of one of the smaller boxes which the container is intended to hold.

2. A display container for boxes of merchandise, said container having a hinged cover portion for a portion only of the top 100 surface of the container and an independent cover portion for the remaining surface of the top of the container, all of said top portions being paneled off to form panels each of which is printed like the top surface of 105 the boxes which the container is intended to hold.

3. A display container for boxes of merchandise, said container having a hinged cover for a portion of the top and an independent cover portion for the remaining surface of the top of the container, all of 110 said top portions being paneled off to form panels each of which is printed like the top surface of the boxes which the container is 115 intended to hold, the said hinged cover portion being of a size and shape equal to a multiple of the top face of the smaller boxes within the container and said hinged cover and other cover portions having the panels 120 marked in replica of the markings on the top of the boxes within the container.

4. A display container for boxes of merchandise, formed of a single sheet of material blanked out, said blank having a body 125 portion which forms the top of the container when set up, two side and two end flap portions which form the sides and ends of the container, one of said side flap portions having an extension which forms the 130

- bottom of the container, tuck flaps connecting the said side and end forming flaps, said top forming portion being printed on its upper face in panel arrangement, each 5 panel being printed like the top face of each of the boxes which the container is intended to hold, the said top being slit to form a portion thereof into a hinge cover comprising one or more of said printed panel por- 10 tions complete, said hinge cover having also a tongue integral therewith which is slit out of the front side portion of the container, said cover portion extending from the front to the rear edge of the top and folded trans- 15 versely of its middle, the rear edge of said cover portion being creased to form the hinge and having a slit therein to receive the said tongue when said hinged cover is folded upon itself. 20 5. A display container for boxes of merchandise, formed of a single sheet of material blanked out, said blank having a body portion which forms the top of the container when set up, two side and two end 25 flap portions which form the sides and ends of the container, one of said side flap portions having an extension which forms the bottom of the container, tuck flaps connecting the said side and end forming flaps, said 30 top forming portion being printed on its upper face in panel arrangement with a plurality of panels, each panel being printed like the top face of each of the boxes which the container is intended to hold, the said 35 top being slit to form a portion thereof into a hinge cover comprising some of said printed panel portions, said hinged cover having also a tongue integral therewith which is slit out of the front side portion of the con-
- tainer, said cover portion extending from 40 the front to the rear edge of the top and folded transversely of its middle, the rear edge of said cover portion being creased to form the hinge and having a slit therein to receive the said tongue when said hinged 45 cover is folded upon itself, the panel portions of said hinge cover being printed in such manner that when the cover is opened and folded the printed matter both on the front and the rear panel will read from the 50 top down.
6. A display container for boxes of merchandise, said container being formed of a single sheet of material blanked out, said blank having a body portion which forms a 55 cover for the container when set up and flap portions which form the bottom, the two sides, and two ends of the container, said cover forming portion being printed on its upper face in panel arrangement represent- 60 ing a plurality of panels, each panel being printed like the top face of each of the boxes which the container is intended to hold, the said cover being slit to form a portion thereof into a smaller hinge cover comprising one or more of said printed panel portions, said hinge cover portion extending from the front to the rear edge of the top and folded transversely of its middle be- 65 tween two panel portions, the rear edge of 70 said hinged portion being creased to form the hinge.

In testimony whereof I affix my signature, in presence of two witnesses.
